RAILWAY SIGNAL TORPEDO

Filed May 15, 1928

UNITED STATES PATENT OFFICE.

EDWARD A. SCHOOLEY, OF DORMONT, PENNSYLVANIA.

RAILWAY SIGNAL TORPEDO.

Application filed May 15, 1928. Serial No. 277,840.

This invention relates to railway torpedoes used on railways as audible signals and more particularly to torpedoes embodying an explosive charge, an enveloping casing of fibrous material and a ductile metal strip for detachably securing the torpedoes to the rails of a railway track.

The principal object of this invention is to provide a novel form of enveloping casing 10 composed of fibrous material, such as heavy paper, said casing being so formed that the torpedo may be readily and quickly assembled by unskilled workmen and thus reduce the cost of production.

Another object is to provide a novel manner of mounting the ductile metal retaining strip in the torpedo.

A further object is to provide a torpedo having the novel construction, design and combination of parts hereinafter described and illustrated in the accompanying drawings.

In the drawings:

Figure 1 is a plan of a torpedo constructed 25 in accordance with this invention.

Figure 2 is a plan of the torpedo case before it is assembled and showing the attaching strap and explosive tablet in position.

Figure 3 is a sectional view on the line 30 III—III of Figure 2.

Figure 4 is a plan of the strap-locking member.

Figures 5 and 6 are modified forms of the locking member.

Figure 7 is a plan view of a strap-carrying member separate from the main casing, the attaching strap shown locked in this carrying member by the locking member of Figure 5.

Referring more particularly to the drawings which illustrate my invention, the letter A designates the enclosing fiber casing of the torpedo as a whole, which is formed from a flat piece of heavy paper or fiber board, cut in the form of a Maltese cross. The rectangular or square center 2 of the casing is depressed to form a concave depression 2^a in the casing blank to receive a preformed explosive tablet 3, and the arms of the cross form flaps 4, 5, 6 and 7 adapted to be folded over the explosive tablet 3 to close the casing. The flaps 4 and 5 are no more than half the width of the rectangular center so that when they are folded over the explosive tablet they do not overlap, while the flaps 6 and 7 are of substantially the

same size as the rectangular center so that 55 they overlie the entire rectangular center and one flap completely overlaps the other.

In the preferred form of my invention the flap 6 is provided with a rectangular slot 8 to receive a strap of ductile metal 10, which 60 is used to detachably hold the completed torpedo in position on the rail of a railway. The strap of metal 10 is adapted to be looped or bent upon itself in substantially U-shape and to have its end projected through the slot 65 8 and a locking member or sheet of fiber 12 is adapted to be inserted through the loop so as to overlie the flap 6 and to bridge the major portion of the slot 8 and thus lock the strap 10 in position. The locking member or sheet 70 12 is of substantially H-shape in plan and its legs or projecting portions 14 are adapted to project outwardly on each side of the strap of metal 10 and its connecting portion 15 is adapted to bridge the slot 8. 75

If desired, the slot 8 may be omitted from the flap 6 and a separate strap-carrying member 6^a, shown in Figure 7, may be used. The strap-carrying member 6^a is provided with a slot 8^a to receive the strap 12, which is shown 80 locked in position by the modified locking member or sheet 12^a, of Figure 5, which is provided with legs 14^a and a bridging or connecting portion 15^a.

The strap-carrying member 6^a may be 85 mounted over the flaps 4 and 5 and under the flaps 6 and 7, or may be mounted under the flaps 4 and 5 if desired.

It will also be understood that when the strap-carrying member 6^a is used, the flaps 6 90 and 7 may be no more than half the width of the rectangular center 2, like the flaps 4 and 5, if desired.

The strap-locking member of Figure 5 has its side edges adapted to parallel the longitudinal edges of the strap-receiving slot curved so as to facilitate the mounting of the member under the strap 10. 95

In Figure 6 I have shown a strap-locking member having the same structural outline as the member of Figure 5, except that its curved side edges are curved on a slightly shorter radius. The same reference numerals are used to designate the parts of this locking member as are used to designate the parts of the construction shown in Figure 5, except that they are primed by the letter b. 100

In the formation of the torpedoes of this

invention a coating of water-proof cement is applied to the concave depression 2^a prior to the insertion of the explosive tablet 3, and then a coating of the same cement is applied 5 to the tablet 3 and surrounding portions of the center 2 of the casing, to secure the flaps 4 and 5 in position when they are folded over the explosive tablet. After the flaps 4 and 5 are folded into position they will also be coated with cement and the flap 6 will be folded over in position. A layer or coating of cement will then be applied over the flap 6 and the flap 7 will be folded over and secured.

After the casing has been firmly cemented 15 together, the assembled torpedo is then placed in a suitable mold or die and pressed to finally compact the whole structure and complete the shaping thereof. After the torpedo has been pressed to final shape it is 20 coated with a suitable water-proofing compound such as varnish, shellac or the like, and then, if desired, before such coating is dry, one or more sides of the torpedo may be sanded and the sand will adhere to the sticky 25 coating, thus forming an abrasive surface.

While I have shown and described certain specific embodiments of my invention, I do not wish to be limited thereto since other modifications may be made without departing from the scope thereof as defined in the appended claims.

I claim—

1. A fiber case railway torpedo comprising an enclosing case made in the form of a 35 Maltese cross and having its rectangular center depressed to form a concave depression for holding the explosive tablet, the arms of said cross forming flaps for closing over the explosive, at least one of said flaps being of 40 the same size as said rectangular center and being provided with a centrally arranged elongated rectangular opening, a ductile metal strap adapted to be bent upon itself to form a loop and the closed end of said loop being 45 inserted through said openings, and a substantially H-shaped fiber-locking sheet mounted through said looped strap with its

connecting portion bridging said opening and its legs overlying said flap.

2. A fiber case railway torpedo comprising 50 an enclosing case made in the form of a Maltese cross and having its rectangular center depressed to form a concave depression for holding the explosive tablet, the arms of said cross forming flaps for closing over the explosive, two of said flaps having a length approximately half the width of said 55 rectangular center portion so as to meet at the center lines of said cross when folded back over the explosive, the other two flaps being of a size substantially the same as said rectangular center portion, a preformed explosive tablet mounted in said depression, said first named two flaps being adapted to be folded back over said tablet, and said other 60 two flaps being adapted to be folded back one over said first two flaps and the other over all of said flaps, said one of said second named two flaps directly overlying said first two flaps being provided with a centrally arranged elongated rectangular opening, a 65 ductile metal strap adapted to be bent upon itself to form a loop and the closed end of said loop being inserted through said opening and a substantially H-shaped fiber-locking sheet mounted through said looped strap with its 70 connecting portion bridging said opening and its legs overlying said flap.

3. In a fiber case railway torpedo, a substantially rectangular casing element adapted 75 to have a ductile metal attaching strap secured thereto, said element having a centrally arranged elongated rectangular opening, said ductile metal strap being adapted to be bent upon itself to form a loop and the closed end of said loop being inserted through said opening, and a substantially H-shaped fiber-locking sheet mounted through said looped strap with its connecting portion bridging said opening and its legs overlying said element. 80

In testimony whereof, I have hereunto set my hand.

EDWARD A. SCHOOLEY.
